UNITED STATES PATENT OFFICE.

WILLIAM J. DUNN, OF MONTREAL, QUEBEC, CANADA.

INTERNAL-COMBUSTION MOTOR.

1,407,393.

Specification of Letters Patent. Patented Feb. 21, 1922.

Application filed February 25, 1920. Serial No. 361,314.

To all whom it may concern:

Be it known that I, WILLIAM J. DUNN, a subject of the King of Great Britain, and resident of the city of Montreal, in the 5 Province of Quebec and Dominion of Canada, have invented certain new and useful Improvements in Internal-Combustion Motors, of which the following is a full, clear, and exact description.

10 This invention relates to improvements in internal combustion motors, and the object of the invention is to provide an engine which may be produced at low cost and which will have a high rate of efficiency.

15 The device consists essentially of an engine in which valves of the piston type are used, each valve serving two cylinders. In order to economize in manufacture, the cylinders and their valves are preferably cast 20 en bloc in pairs. If desired, all the cylinders of an engine may be cast en bloc. The disadvantages incident to the use of a muffler are overcome by passing the exhaust in proximity to the fly wheel, which is in the 25 nature of an impulse turbine, so that the pressure of the exhaust in place of being effective as a back pressure on the engine is effective to increase the power.

20 In the drawings which illustrate the invention;

Fig. 1 is a plan view of an engine with the cylinder cover removed.

Fig. 2 is a section on the line 2—2, Figure 1.

35 Fig. 3 is a section on the line 3—3, Figure 2.

Fig. 4 is a fragmentary interior elevation of the fly wheel casing showing the exhaust gas screen.

40 Fig. 5 is an enlargement of the valve shown in Fig. 2.

Fig. 6 is a section of the valve on the line 6—6, Figure 5.

Referring more particularly to the drawings, 45 11 designates a crank case formed of as many parts as desired and containing a crank shaft 12 journaled in bearings 13.

The cylinder bloc 14 is mounted on the crank case in the usual way and in the particular design illustrated is provided with a cover 15, water ports 16 being provided to connect the cooling jacket 17 of the cylinders with the cooling jacket 18 of the cover. 50

The valves are of the piston type and the 55 valve cylinders 19 are located between the engine cylinders 20 on each side of the lon-

gitudinal axis of the engine and as close as possible to the cylinders, in order to reduce the length of the passages between the valves and cylinders. In order to lighten 60 the structure, it is preferred to cast the cylinder bloc of a suitable aluminum alloy and provide bushings 21 of steel or other suitable material in the engine and valve cylinders. For convenience and simplicity, it is also 65 preferred to locate the inlet valves 22 on one side of the longitudinal axis and the exhaust valves 23 on the other side, using separate half-time shafts 24 driven by gears 25 from the crank shaft to operate the valves. To 70 secure smooth motion and avoid the use of springs, it is preferred to operate the valves by means of eccentric rods 26 similar to those used in the valve motions of steam engines. By this arrangement, the gas passages are of the shortest possible length and the inlet manifold 27 and exhaust manifold 28 are also of the least possible length. 75

The exhaust manifold 28 is connected by a conduit 29 with a casing 30 which surrounds 80 the fly wheel 31, the conduit entering the casing tangentially. An exhaust outlet pipe 32 is provided leading tangentially from the casing, either in alignment with the conduit 29 or at any desired angle thereto. The edge of the fly wheel is provided with a series of pockets 33 which function similarly to the blades of a turbine. A valve 34 is provided in the conduit 29 close to the fly wheel and an ignition device 35 is 85 provided between this valve and the fly wheel, for the purpose of igniting any unburned gas and preventing the discharge of an explosive mixture. In order to reduce or eliminate the pulsations of the liberated 90 exhaust, a screen 36 is provided between the casing and the outlet pipe 32, the perforations being located in approximately a triangular formation, as shown in Figure 4, 95 so that the single perforation at the apex of the triangle is first uncovered by the edge of a fly wheel pocket. As the pocket edge advances, the number of perforations uncovered in each row increases until the row occupies the full width of the pocket. In 100 this way, the pressure is gradually reduced and the pulsating sound caused by a sudden liberation of a large amount of high pressure gas is eliminated. 105

The valves are exactly alike throughout 110 the motor, so that a description of one suffices for all. The valve comprises outer and

inner sleeves 37 and 38 respectively, which are slidable relatively to one another and are both operated by a single wrist pin 39 to which the eccentric rod 26 connects. This 5 wrist pin passes through a block 40 mounted in the inner sleeve, which serves to confine the gases to the upper part of the sleeve and also forms a centering guide for the eccentric rod. Relative movement of the sleeves 10 is permitted by slots 41 in the outer sleeve, which permit the wrist pin to move up or down a certain distance before reaching the ends of the slots and imparting movement to the outer sleeve. It has previously been 15 stated that a single valve controls the inlet or exhaust of two cylinders and it is therefore necessary that the gas ports be uncovered at different times. To enable this to be done, the gas passages 42 and 43 extend to different levels of the valve cylinder and the ports 44 and 45 are arranged at these different levels. The outer sleeve 37 has 20 ports 46 and 47 adapted to register one at a time with the ports 44 and 46. These 25 outer sleeve ports are located a lesser vertical distance apart than the ports 44 and 45. The inner sleeve is provided with ports 48 and 49 adapted to register at different times with the ports 44 and 46 and 45 and 30 47 respectively. The ports 48 and 49 are approximately the same vertical distance apart as the ports 44 and 45. The length 35 of the slots 41 may be expressed as the diameter of the wrist pin 39, plus the vertical measurement of the ports 46 and 48 or 47 and 49, plus the maximum lap between these 40 ports. Gas is admitted to or emitted from the upper part of the inner sleeve 38 through ports 50 formed in both sleeves at a point 45 in the circumference between the ports 46, 48 and 47, 49. These ports are elongated vertically as shown, so as to reduce the proportion of sleeve circumference taken up by them and yet provide at the extremes 50 of sleeve movement the necessary maximum area, which is approximately equal to the cross sectional area of the manifold. In order to control the relative movement of the sleeves, a dog 51 is resiliently mounted in 55 any suitable manner and position, for example in the recess 53, and when so arranged, operates through a slot in the valve cylinder bushing to engage in either the head or the foot of an eye-shaped slot 52 formed in the outer sleeve. The inner sleeve carries a cam 54 which travels in the upright portion or stem of the slot to engage the dog and force the same out of the head or foot of the slot. 60 The operation of the device is extremely simple. Assuming an inlet valve to be in the position shown in Figure 5, initial movement is imparted to the engine and the inner sleeve descends, bringing its port 48 into 65 register with the port 46 of the outer sleeve,

which is in register with the port 44. Gas then flows through the ports until the port 48 passes out of register with the port 46. As the inner sleeve moves downwardly, the cam 54 thereon throws back the dog 51 from 70 the foot of the slot 52 and releases the outer sleeve, so that when the port 48 has passed out of register with the port 46 and the wrist pin reaches the bottoms of the slots 41 the outer sleeve will be free to move. 75 It will be noted that, as the inner sleeve moves down, its port 49 passes out of register with the port 47 and is out of register when the outer sleeve commences to move down with the inner. This condition prevails until the outer sleeve has been moved down to bring its port 47 into register with the port 45 and the sleeve has been locked by entrance of the dog 51 in the head of the slot 52 and the inner sleeve moved up to 80 bring its port 49 into register with the port 47. Gas now flows through the aligned ports to the second cylinder until the port 49 passes the port 47. As the inner sleeve moves up, its cam 54 throws the dog out 85 of the head of the slot 52, so that when the wrist pin reaches the tops of the slots 41 the outer sleeve will be free to move with the inner sleeve and resume the position shown in Figure 5. It will be noted that although 90 the port 48 registers with the port 46 during the independent rise of the inner sleeve, there will be no gas flow through the passage 42 owing to the fact that the port 46 is out of register with the port 44. The 95 entire cycle of operations in the valve for either cylinder is completed in exactly one revolution of the half-time shaft 24, so that the engine operates on the four-cycle principle. The difference in level between the 100 ports 44 and 45 is the stroke of the valve so that communication with the engine cylinders is established at the end of a quarter revolution of the engine shaft, thus enabling the cranks to be set opposite one another in 105 the usual manner. The exhaust valve is constructed and operates in exactly the same manner as the inlet valve, but naturally the eccentric rod is differently disposed, so that the exhaust valve for one pair of cylinders 110 is at about half stroke when the inlet valve is at full stroke. The exhaust from the cylinders flows out of the valves through the ports 50, manifold 28 and conduit 29 and impinges on the fly wheel so that a certain 115 portion at least of its velocity is imparted to the fly wheel. A very hot spark is produced at the ignition plug 25 so that any unburned gases in the exhaust will be ignited and burned, thus preventing the discharge of a combustible mixture from the pipe 32. The valve 34 will prevent any such combustion of gases creating a back 120 flash in the conduit 39 and manifold 28. 125 Owing to the use of steel bushings in the 130

engine and valve cylinders, the construction may be largely of aluminum alloy with the result that a very light motor will be produced. The arrangement of valves and use of eccentrics greatly simplifies the construction. The escaping gases tend to contribute power to the engine instead of tending to detract from the power, as is usual.

Having thus described my invention, what

10 I claim is:—

1. An internal combustion motor comprising a pair of power cylinders, a pair of valve cylinders and passages connecting each valve cylinder with each power cylinder, said passages communicating with the valve cylinders at different levels.

2. In an internal combustion engine, a valve comprising a pair of independent movable sleeves and an operating means therefor comprising a movable member, and a single pin connecting said member to both sleeves.

3. In an internal combustion engine, a valve comprising a pair of independent movable sleeves, and an operating means therefor rigidly connected to one of said sleeves and slidably connected to the other sleeve.

4. A device according to claim 3, in which the sleeves are arranged one within the other.

30 5. In an internal combustion engine, a pair of cylinders and a valve serving both cylinders of the pair including a pair of relatively movable sleeves, an operating means for said sleeves rigidly connected to one of said sleeves and slidably connected to the other sleeve, means for releasably locking said second sleeve and means carried by the first sleeve for disengaging said locking means from the second sleeve.

40 6. A device according to claim 5, in which the first sleeve is mounted within the second sleeve and the second sleeve is provided with an eye-shaped slot adapted at top and bottom to receive the locking means and in its intermediate portion to receive the disengaging means of the first sleeve.

7. In an internal combustion engine, a pair of power cylinders, a pair of valve cylinders, separate passages connecting each power cylinder with each valve cylinder, a pair of sleeves arranged one within the other in each valve cylinder having ports therein adapted to register with said connecting passages, means for releasably locking one of said sleeves against sliding movement, and means carried by the other sleeve for releasing said locking means and operating means for said sleeves adapted to bring the sleeve ports into registration with one another and with the passages at predetermined times.

8. A device according to claim 7, in which the ports of the sleeves are so positioned that the ports pertaining to one power cylinder are out of register when the ports of the other cylinder are in register.

9. A device according to claim 7, in which the ports of the outer sleeve are positioned so that when one port registers with the passage connecting to one cylinder the other port is out of register with the passage connecting to the other cylinder, and the ports of the inner sleeve positioned to be out of register with the first mentioned outer sleeve port when the latter registers with the first mentioned passage, and the other inner sleeve port to be in register with the second outer sleeve port when the same is out of register with the second passage.

10. In combination with a device according to claim 7, means for holding the outer sleeve with a port in register with a passage, while a part of the outer sleeve passes into and out of register with the outer sleeve port, and means for releasing the outer sleeve for movement with the inner sleeve.

11. In combination with a device according to claim 7, means for holding the outer sleeve with a part thereof out of register with a passage and in register with an inner sleeve port, while said inner sleeve port passes out of register with the outer sleeve port, and means for releasing said outer sleeve for movement with the inner sleeve sufficient to bring the outer sleeve port into register with the passage and for releasing the holding means whereby said outer sleeve will be held with its port in register with a passage, while the inner sleeve port is moved into and out of register with the outer sleeve port.

12. In an engine, a valve cylinder having a passage leading into the side thereof, a pair of sleeves slidable one within the other and in said cylinder, each of said sleeves having a port adapted to register with the passage, means for reciprocating each of said sleeves within the cylinder, and means for holding one of said sleeves stationary during a part of the movement of the other sleeve, whereby the relative position of said sleeve ports will be changed.

13. A device according to claim 12, in which the holding means is in engagement with one sleeve during the movement of the other sleeve for a distance equal to the sum of the port width plus any lap between the parts.

14. A device according to claim 12, in which the holding means comprises a dog operatively engageable with one of said sleeves at two points, and a cam carried by the other sleeve adapted to successively disengage the dog from both points of engagement with the other sleeve.

15. A device according to claim 12, in which both sleeves are connected to a single operating member by means of a wrist pin stationary in one sleeve and slidable, within limits, in the other sleeve.

16. A device according to claim 12, in

which the locking means includes a stationary dog, a pair of spaced recesses therefor in one of said sleeves, a cam carried by the other sleeve operating in a recess in the 5 first sleeve and engageable with said dog to eject the same from either of the recesses of the first sleeve.

17. In an internal combustion engine, a valve cylinder, a bushing of different material therein, a pair of sleeves slideable one 10 within the other and within said bushing, a

passage leading to the valve, ports in said sleeves in constant register with one another and with the passage, a head closing one end of the cylinder, a plug in the inner sleeve, 15 a wrist pin passing diametrically through said plug and both sleeves and securing the plug, and a valve operating device connected to said wrist pin.

In witness whereof, I have hereunto set 20 my hand.

WILLIAM J. DUNN.
